Application August 3, 1938, Serial No. 222,810
In the Netherlands August 25, 1937

4 Claims. (Cl. 179—171)

The invention relates to a high or intermediate frequency thermionic amplifiers wherein use is made of volume control brought about by variation of the grid bias of at least one of the amplifying tubes. The invention relates more particularly to a high or intermediate frequency amplifier wherein grid bias of the tubes to be controlled is taken from a potentiometer resistance which is connected in parallel with a part of a source of voltage the other part of which furnishes the anode voltage.

Such a circuit arrangement is preferably utilized in a television receiver since in this case it is frequently impossible to provide in that portion of the cathode lead which is common to the grid circuit and to the anode circuit, a resistance which serves for the automatic supply of the grid bias. The reason for this lies in the fact that in a television receiver the anode current of each of the tubes, or at least of the final amplifying tube, frequently contains a direct current component which determines the average brightness of the received image and of which it is undesired to be supplied to the grid of the high or intermediate frequency amplifying tubes.

According to the invention, an improvement in the circuit arrangement with which the invention is concerned, is obtained by providing filters which suppress the high or intermediate frequency oscillations in the conductors by means of which the grid and the cathode of the tube or tubes to be controlled are connected to the potentiometer resistance from which the variable grid bias is taken.

The conductors by means of which the grid and the cathode are connected to the potentiometer resistance preferably have connected in them screened resistances the screening of which is earthed.

The invention will be explained more fully with reference to the accompanying drawing wherein:

Fig. 1 represents a circuit arrangement with which the invention is concerned.

Fig. 2 represents one mode of realization of a high or intermediate frequency amplifier according to the invention.

The circuit arrangement shown in Fig. 1 comprises a high frequency amplifying tube 1 to the input circuit 2 of which the high frequency oscillations received in an aerial 3 are supplied and the output circuit of which includes an impedance 4 from which the oscillations amplified by the tube 1 are taken. The anode voltage of the tube 1 is determined by the drop of voltage in a re-

sistance 5 across which occurs part of the voltage of a source of voltage 6, which part is determined by the ratio between the resistances 5 and 7. The grid bias of the tube 1 is taken from a potentiometer resistance 8 which is connected in parallel with that part of the source of voltage 6 which is determined by the value of the resistance 7. Furthermore, decoupling condensers 9 and 10 are provided which bridge the resistances 8 and 7 respectively for the oscillations to be amplified while a condenser 11 is connected in parallel with the source of voltage 6.

The above described circuit arrangement has the drawback that for the oscillations to be amplified the condensers 9 and 10 do not form a complete short circuit but that due to the dielectric losses in these condensers and to the self-inductance of the connecting wires, high frequency voltages are set up between the points denoted by 12 and 13 and the earth. These voltages may be capacitatively transmitted to the aerial 3, which gives rise to an undesired feedback. This drawback arises in particular if the amplifier is constructed as shown in Fig. 2 wherein the volume control of the apparatus can be effected from a distance.

In the embodiment shown in Fig. 2 the ends of the resistance 8 are connected by means of conductors 14 and 15 to the amplifier proper, the point 12 being connected through the intermediary of a conductor 17 to a slide contact 16 on the resistance 8. Since the conductors 15 and 17 are capacitatively coupled with the aerial 3, there exists with this circuit arrangement a very great possibility that a high frequency voltage set up between the points 12 and 13 and the earth is supplied via the aerial 3 to the grid of the tube 1.

According to the invention, in order to remove this drawback the conductors by means of which the grid and the cathode of the tube 1 are connected to the potentiometer resistance 8 have connected to them screen resistances 18 and 19 of which the screening member is earthed. These resistances act as filters which suppress the high frequency voltages set up between the points 12 and 13 and the earth, owing to which it is achieved that between the terminal points and the slide contact 16 of the resistance 8 and the earth there is no high frequency voltage. The resistance 19 is provided in the conductor connecting the cathode to the potentiometer resistance 8 in such manner that the anode direct current does not pass through this resistance.

A further advantage of the circuit arrange-

ment is that the resistance 19 in series with the resistance 8 is connected in parallel with the resistance 7, it being thus ensured that even with the maximum amplification by the tube 1, which may be attained by adjustment of the point 16, a negative voltage is supplied to the grid of the tube 1.

Having described our invention, what we claim is:

- 10 1. An amplifier comprising a thermionic tube having an anode, control electrode and cathode, a tuned resonant circuit connected between the control electrode and cathode, a potentiometer having two end terminals and a tapped terminal included in the connection of the tuned resonant circuit to the cathode, a first shielded resistor connected from the tuned resonant circuit to said tapped terminal of the potentiometer, a second shielded resistor connected to the cathode and 20 one of said end terminals of the potentiometer, a source of voltage for supplying energy to the anode of the tube, a voltage divider connected across the source of voltage, and connections from said second shielded resistor to a portion of 25 the voltage divider.

2. A radio frequency amplifier comprising a thermionic tube having an anode, control elec-

trode and cathode, a source of voltage for supplying said another with power, volume control means comprising a potentiometer connected in parallel with at least a portion of said source of voltage, and low pass filters connected between said potentiometer and said control electrode and between said potentiometer and said cathode for suppressing radio frequency components. 5

3. A radio frequency amplifier as claimed in claim 2 wherein said low pass filters comprise 10 shielded resistances, the shields of said resistances being grounded.

4. A radio frequency amplifier comprising a thermionic tube having an anode, control electrode and cathode, a tuned resonant circuit connected between the control electrode and cathode, a source of voltage for supplying said anode with power, volume control means comprising a potentiometer connected in parallel with at least a portion of said source of voltage, a first low pass filter connected between a portion of the potentiometer and said tuned resonant circuit, and a second low pass filter connected between said potentiometer and said cathode for suppressing radio frequency components. 15 20 25
